UNITED STATES PATENT OFFICE.

PLEASANT T. LEMASTER, OF SPARTANBURG, SOUTH CAROLINA.

BILL-FILE.

No. 818,835.

Specification of Letters Patent.

Patented April 24, 1906.

Application filed April 1, 1905. Serial No. 253,286.

To all whom it may concern:

Be it known that I, PLEASANT T. LEMASTER, a citizen of the United States, residing at Spartanburg, in the county of Spartanburg and State of South Carolina, have invented certain new and useful Improvements in Bill-Files, of which the following is a specification.

This invention has relation to bill-files; and 10 it consists in the novel construction and arrangement of its parts, as hereinafter shown and described.

The object of the invention is to provide a file for holding bills, papers, &c., which is simple and cheap in construction and the parts 15 of which are so arranged that any particular bill or paper upon the file may be easily and readily removed without disturbing the order of arrangement of the other bills or papers.

20 The invention consists primarily of a piece of steel-spring wire provided with a means whereby it may be attached to a wall or other stationary object. The ends of the said wire are pointed and extend generally toward 25 each other. Immediately behind the point of each end of the wire is located a groove and an eye, the groove and eye of one end being 30 adapted to receive the groove and eye of the opposite end when the two ends of the wire are locked together. Also either eye may be used for holding a piece of cord or twine upon 35 which the bills or papers may be passed from the file.

In the accompanying drawings, Figure 1 is 40 a side elevation of the bill-file. Fig. 2 represents a group showing the upper and lower ends of the wire, and in said group, *a* is a front elevation of the lower point of the wire, *b* is a longitudinal sectional view of the lower 45 point of the wire, *c* is a longitudinal sectional view of the upper point of the wire, and *d* is a rear elevation of the upper point of the wire. Fig. 3 is a front elevation illustrating one 50 means for attaching the bill-file to the wall, and Fig. 4 is a front elevation illustrating a modified means for attaching the bill-file to the wall.

The bill-file consists of a spring-wire 1. Said wire is preferably made of steel. The 55 upper portion 2 of the said wire 1 is curved substantially in the form of the arc of a circle and is provided at its lower end with an inwardly-inclined point 3. Immediately above said point 3 is located an eye 4, and above the 55 said eye 4 and leading into the same and lo-

cated upon the inner face of the wire is a groove 5. The lower portion 6 of the bill-file 1 is bent toward the front and merges into the portion 7, which is so positioned under tension from the curved portion 6 as to normally incline away from the upper portion 2 of the wire 1, as indicated by the dotted lines in Fig. 1. The upper end of the portion 7 is provided with outwardly-inclined pointed end 8, and immediately below the said pointed end 8 is located an eye 9, and immediately below the said eye and extending down in the outer side of the portion 7 is a groove 10.

In the form of the invention as illustrated in Figs. 1 and 3 the wire 1 is split longitudinally at the point 11 and may receive the head of a nail attached to a wall, (not shown,) whereby the bill-file is supported upon the wall. In the form of the invention as illustrated in Fig. 4 the wire 1 is not split, but is 75 twisted into a loose knot 12, which is adapted to receive the nail in the manner as above described for the split portion 11.

When the ends of the portions 2 and 7 are interlocked, the point 3 of the portion 2 enters the eye 9 of the portion 7 and the point 8 of the portion 7 enters the eye 4 of the portion 2. In the operation of interlocking the grooves 5 and 10 serve as guides for directing the points 3 and 8 into the eyes 9 and 4, respectively. It will thus be seen that when the ends of the portions 2 and 7 are interlocked the points 3 and 8 are concealed, and the bills may be passed from the portion 6 along the portion 7 and upon the portion 2 90 without interference on the part of the said points, and that thus the said bills may be supported, and any particular bill may be removed by disengaging the ends of the portions 2 and 7 without disturbing the relative 95 arrangement of the remaining bills. Furthermore, a string or twine 13 (indicated by dotted lines in Fig. 1) may be inserted through either the eye 9 or the eye 4, and the bills or papers may be passed from over the portion 100 2 or portion 7 upon the said string in the same order in which they were filed. Thus the file may be cleared of bills and papers when desired.

It will be observed that the ends of the portion 7 and the portion 2 are alike in construction, but that the parts thereof are oppositely disposed and that they engage and interlock with each other in a similar manner.

Having described my invention, what I

claim as new, and desire to secure by Letters Patent, is—

1. A bill-file consisting of a wire having ends of like construction with the parts there-
of oppositely disposed, said ends being point-
ed, eyes located adjacent each said point, the
eye of one end adapted to receive the point of
the other end and vice versa.

2. A bill-file consisting of a wire having
ends of like construction with the parts there-

of oppositely disposed, said ends being point-
ed, each end having an eye located adjacent
said point and grooves leading toward said
eyes.

In testimony whereof I affix my signature 15
in presence of two witnesses.

PLEASANT T. LEMASTER.
